UNITED STATES PATENT OFFICE.

JOSEPH B. HOLDEN, OF SYRACUSE, NEW YORK, ASSIGNOR TO REMINGTON TYPEWRITER COMPANY, OF ILION, NEW YORK, A CORPORATION OF NEW YORK.

TYPEWRITING MACHINE.

Application filed March 27, 1922. Serial No. 547,128.

To all whom it may concern:

Be it known that I, JOSEPH B. HOLDEN, a citizen of the United States, and resident of Syracuse, in the county of Onondaga and 5 State of New York, have invented certain new and useful Improvements in Typewriting Machines, of which the following is a specification.

My invention relates to typewriting machines and more particularly to so-called portable machines intended to be inclosed and transported in a carrying case.

When a typewriting machine is carried about there is danger of injury to, and perhaps breakage of, parts of the escapement mechanism due to the fact that the weight of the carriage comes on the feed dogs unless special provision is made to provide against it, and the force of the jars or 20 jolts to which the machine may be subjected comes against the feed dogs with the consequent liability of injury.

One of the objects of my invention is to overcome this difficulty.

25 A second object of the invention is to insure the proper positioning of the carriage preparatory to inclosing the machine within its case.

A still further object of my invention is 30 to provide improved means whereby in attaining this last mentioned result the carriage will be released from the restraint of its escapement, and thus at the same time accomplish the first mentioned object.

35 To the above and other ends which will hereinafter appear, my invention consists in the features of construction, arrangements of parts and combinations of devices set forth in the following description and 40 particular pointed out in the appended claims.

In the accompanying drawings wherein like reference characters indicate corresponding parts in the different views,

45 Figure 1 is a fragmentary side elevation of the rear portion of the machine shown contained within its closed carrying case, the latter being in section and the carriage shown locked in its centered position.

50 Figure 2 is a like view of the same with the cover of the carrying case removed and the carriage lock released.

Figure 3 is a fragmentary rear elevation of the machine shown contained within its

closed carrying case, the latter being in section and the carriage shown locked in its centered position. 55

Figure 4 is a detail fragmentary horizontal sectional view of the machine taken on the line 4—4 of Fig. 2 and looking in 60 the direction of the arrows at said line.

Figure 5 is a detail perspective view of the spring pressed carriage locking member.

Figure 6 is an enlarged detail vertical sectional view of the finger wheel for the 65 platen and some of the associated parts, the section being taken longitudinally of and centrally through the platen.

Figure 7 is a detail perspective view of the carrying case shown closed and inclosing the machine. 70

I have shown my invention in the present instance embodied in a Remington portable machine, many of the features of which are shown in the following patents and pending 75 applications: A. W. Smith, Pat. No. 1,342,513, dated June 8, 1920; J. B. Holden, Pat. No. 1,386,256, dated Aug. 2, 1921; J. B. Holden, app. Sr. No. 469,458, filed May 14, 1921; J. B. Holden, app. Sr. No. 541,355, 80 filed Mch. 6, 1922; J. B. Holden, app. Sr. No. 330,747, filed Oct. 15, 1919; G. A. Seib, app. Sr. No. 529,415, filed Jan. 16, 1922. It should be understood, however, that the invention is not restricted to embodiment in 85 a machine of this style.

From certain aspects of my invention it is in the nature of improvements on the construction disclosed in my above mentioned application, Sr. No. 330,747. 90

The Remington portable machine is provided with a carrying case, the cover of which can be closed only when collapsible parts of the machine are moved to compact relation with the remainder of the machine 95 and when the carriage is properly centered on its support, as pointed out in my above mentioned application, Sr. No. 330,747. In said application means are also disclosed for compelling the operator to free the carriage from restraint of its escapement mechanism before the machine can be inclosed within its case. By my present invention I provide improved means for locking the carriage in its centered position which must necessarily be actuated before the case can be closed, and combined with such means devices whereby when a member of said lock 100

105

is moved to effective position the carriage will be released from restraint of its escapement, and when said locking member is moved to ineffective position the escapement 5 will be rendered effective to restrain the carriage. This affords an assurance not only that the carriage will be released from and restored to control of the escapement at the proper intervals to secure these results, 10 but it also affords an assurance that the carriage lock will be actuated to lock and to release the carriage at the proper intervals.

In the accompanying drawings I have 15 shown only so much of the Remington portable machine as is necessary to arrive at an understanding of my invention in its embodiment therein.

The outer sheet metal frame 1 of the 20 machine contains an inner sheet metal frame 2 by which various working parts of the machine are supported. Among such parts is a carriage supporting case shift frame, such as is illustrated in my above mentioned Patent No. 1,386,256. This case shift frame 25 comprises a carriage support 3 pivoted at 4 on upright arms 5 secured to a rock shaft 6 pivoted at its ends, as at 7, to the inner frame, so that the carriage support may receive a case shifting movement fore-and-aft 30 of the machine.

The carriage support has two grooved 35 guide-rails or plates 8 and 9 secured thereto. These guide-rails contain crossed bearing rollers 10 that are received in ways in the rails 8 and 9 and in companion grooved rails or ways 11 and 12 respectively, formed on the bent edge portions of the main base plate 13 of the carriage. This plate has fixed 40 thereto end plates 14 and 15 and such end plates support a platen 16. The carriage is thus mounted to travel from side to side of the machine and support the platen in position to receive the impact of downwardly and rearwardly striking type bars 45 (not shown) on the upper side thereof.

The step-by-step feed movement of the carriage is controlled by escapement mechanism comprising, in the present instance, feed dogs 17 and 18 carried by a key controlled dog rocker and engaging teeth 19 of a feed rack 19. The feed rack is carried by a sheet metal plate 20 which has upwardly and forwardly bent arms 21 and 22. The arm 21 is bent at its free end portion to form a pivot bearing 23 that receives a pivot rod 24 supported in bearings 25 of a bracket which is secured to the base plate 13 of the carriage. The arm 22 is secured 55 by a screw 26 to a block 27 apertured to receive a pivot rod 28 supported in bearings 29 of a bracket plate 30, secured by screws 31 to the base plate 13 of the carriage. Coiled springs 32 surround the pivots 24 60 and 28, and each bears at one end 33 on the

associated bracket plate, and at its other end 34 against the plate 20, and normally holds the feed rack in its effective or engaging position, shown in full lines in Fig. 2. The rack is limited in its movement in this 70 direction by the arms 21 and 22 bearing against the rear ends of two screw stops 35 and 36 respectively, threaded into tapped openings in the bent edge portion 12 of the carriage base plate. Fixed at 37 to the left-hand end of the plate 20, is an upwardly and rearwardly extending feed rack release arm 38 which terminates in a finger piece 39. A forward movement of the finger piece 39 from the full to the dotted line position shown in Fig. 2, is effective to disengage the feed rack from the normally engaged feed dog 18, and thus free the carriage from the restraint of its escapement mechanism. The forward movement of the arm 38 to releasing position is limited by a laterally projecting lug 40 (see Fig. 3) that coacts with a stop 41 formed on the rear edge of the end plate 15, as shown in Figs. 1 and 2.

One of the collapsing parts of the Remington portable machine is the finger wheel 42 which is movable from the dotted line position of use, to the full line compacted position shown in Fig. 3, as pointed out in my hereinbefore mentioned application Sr. No. 330,747. Referring particularly to Fig. 6 it will be seen that the finger wheel 42 is fixed by a screw 43 to a spindle or platen shaft 44 movable longitudinally in the right-hand platen head 45, a spline 46 on the latter extending into a spline groove 47 in the spindle. A pin 48 on the spindle coacts with the spline 46 to limit the outward movement of the spindle and finger wheel, as shown. A flanged bearing sleeve 49 surrounds the spindle 44, and is supported in an opening in the right-hand end plate 14 of the carriage. The bearing sleeve 49 is held in place in the opening in the end plate 14 by a washer 50, riveted to the sleeve. The left-hand end portion of the platen spindle is supported in a bearing sleeve 51, fixed in an opening in the left-hand end plate 15. In this manner the platen is mounted in the 100 platen carriage carrier or carriage, and the finger wheel 42 is connected to turn with the platen but may be moved longitudinally of the platen from the full to the dotted line position in Fig. 3, or vice versa.

The sleeve 51 has a laterally extending slot 52 cut therein to a point where it crosses the bore 53 in the sleeve. A sheet metal locking member or finger 54 is received in the slot 52, and has a movement 115 therein transversely of the spindle 44 from the position shown in Fig. 1, to that indicated in Fig. 2, or vice versa. When a finger wheel is in the expanded or dotted line position, shown in Fig. 3, the left-hand end 120

of the spindle, indicated at 44^a in said figure, is positioned just to the right of the lateral slot 52. If, therefore, at this time the locking finger 54 be in the position shown in Fig. 2, it will prevent the spindle from moving to the left and will lock the finger wheel against movement to its compacted position shown in Fig. 3.

In the present instance the locking member 54 constitutes part of a sheet metal member, designated as a whole by the reference numeral 55. As will be seen upon reference to Fig. 4, this member 55 is pivoted on the shank of an interiorly threaded, headed, screw 56 screwed onto a shoulder screw 57 that passes through an opening in the end plate 15. A rearwardly extending arm of this member 55 terminates in a finger piece 58, by which the member is turned on its pivot. This finger piece is bent laterally to the right from the arm which carries it, so as to extend back of the carriage release arm 38, as shown in Figs. 1 and 3. It follows that a forward movement of the finger piece 58 from the Fig. 2 to the Fig. 1 position will carry the arm 38 with it, thus disengaging the feed rack 19 from the normally engaged dog 18 as shown, and for purposes which will hereinafter appear. This same movement of the finger piece 58 carries the locking finger 54 to the releasing position shown in Fig. 1. The spindle 44 being no longer locked against endwise movement enables the finger wheel 42 to be moved to the full line or compacted position, shown in Fig. 3. Moving the finger wheel to this position is effective to move the left-hand end portion of the spindle across the slot 52 and in the path of the part 54, and therefore to lock the member 55 in the Fig. 1 position. A spring 59 is wound around a pin 60 projecting from the outer face of the end plate 15, and is anchored at one end, as at 61, whereas the free end 61^a of the spring bears against the finger piece 58. The force of this spring is exerted to return the member 55 to the Fig. 2 position when it is freed from restraint of the spindle 44 by moving the finger wheel to the dotted line position in Fig. 3.

The part 55 also carries a locking finger or device 62, which constitutes one member of a lock for locking the carriage in a centralized position on its support 3, as shown in Fig. 1. This finger 62 registers with a slot 62^a in the base plate 13 of the carriage, and is adapted to be moved through said slot at any point in the travel of the carriage from the ineffective position shown in Fig. 2 to the effective position shown in Fig. 1. In this last mentioned position the lower edge portion of the locking finger 62 extends into co-operative relation with a companion locking member carried by the carriage support 3. If, at this time, the carriage is

moved in either direction of its travel from an off-centered position, the locking members will coact when the carriage reaches the centralized position on its support, and will automatically lock the carriage against movement from such position in either direction. The companion locking member on the support 3 is shown detached in Fig. 5, and, in the present instance, comprises a strip of spring metal 63 fastened by a headed screw 64 to the under side of the support 3, the stem of the screw passing through an opening 65 in the locking member. From one edge of the strip 63 is bent an upwardly extending detent 66 having a slot or recess 67 therein. The upper edge of the detent is beveled downwardly and outwardly in opposite directions from the side walls of the recess 67, as indicated at 68. The detent 66 projects up through a slot 69 in the left-hand end portion of the support 3, so that the beveled edge portions 68 of the detent extend above the upper side of the member 3, and are normally maintained in such position by the inherent resiliency or spring pressure of the strip 63. The construction is such that when the locking finger 62 is in the effective position, and the carriage is moved in either direction towards a centralized position, it will bring the lower edge 90 of the finger against one or the other of the two bevels 68 and flex the detent downward. When the centralized position, shown in Fig. 3, is reached the recess 67 will register with the finger 62 and the detent 66 will 100 spring upwardly so as to engage the locking finger on both sides by the side walls of the recess, and thus prevent a movement of the carriage in either direction. When, however, the member 55 is moved to the Fig. 2 position the finger 62 is withdrawn from the recess 67 to free said finger from the detent, and the path of movement of said finger with the carriage is clear of the detent. The carriage is therefore free to move in either 110 direction of its travel so far as the centralized locking means are concerned.

The carrying case of the Remington portable machine comprises a base-board 70 to which the machine is attached by means such as are disclosed in my above mentioned application Sr. No. 469,458, but which need not be described herein. A cover 71 with its fixed rear wall 72, side walls 73, front wall 74, and top wall 75, is detachable from the base-board and may be swung downwardly and forwardly into closed position around the machine on pivot projections 76 on the base-board. By such movement the cover brings contacts 77 thereon into engagement with the carriage, as disclosed in my above mentioned application, Sr. No. 541,355.

From an inspection of Fig. 3 it will be understood that when the finger wheel 42 130

is in the expanded or dotted line position the cover cannot be closed, since the wheel 42 stands in the path of the cover and prevents it from closing. At this time the member 55 is held by its spring 59 in the position shown in Fig. 2; with the locking member 54 preventing a movement of the finger wheel to compacted position, and the locking member 62 withdrawn to ineffective position, 10 and the feed rack 19 normally engaging the dog 18. This is the condition of the machine for use, and from what has been said above it will be understood that this condition of the machine must be changed before it can be inclosed within its carrying case. One such change of condition is to move the finger wheel 42 to the full line position in Fig. 3. But before this can be accomplished it is necessary to move the member 55 by its finger piece 58 to the Fig. 1 position, in order to move the locking finger 54 out of the path of the spindle 44 to which the finger wheel is attached. The finger piece 58 must therefore be moved as stated 20 in order that the finger wheel may be pushed in. This movement of the wheel is effective to project the spindle in the path of the locking finger 54 and hold or lock the member 55 against return movement from the Fig. 1 position to which it has been shifted. The described shifting of the member 55 to the Fig. 1 position also results in moving the locking member 62 to effective position and causes the release arm 38 to be moved 30 forward and release the feed rack 19, thus freeing the carriage from restraint of its escapement mechanism. Being thus freed the carriage moves to the left under the power of its spring drum (not shown) until the carriage is centered on its support, when the member 62 will be automatically engaged by its detent 66 and lock the carriage in its centered position. Should the member 62 happen to be to the left of the detent 66 40 when the carriage is released as described, the carriage will run to the extreme left-hand position of its travel unless restrained. The operator of course knows that the cover cannot be closed when the carriage is in this position, and moves it to the right. When the centralized position is reached the member 62 automatically engages its detent 66 as described, and the carriage is locked in this position against movement in either direction. 50

So far as the construction under consideration is concerned the machine is now in condition for portability or to be inclosed within its case, and the cover may be closed without further obstruction and the machine transported therein. Any shocks or jolts to which the machine is subjected while within the case can result in no injury to the escapement mechanism, since at this time the carriage is disconnected and free

from restraint of its escapement and is held by the lock 62—66.

When the cover is removed and the machine is to be placed in condition for use, it is merely necessary to move the finger 70 wheel 42 from its compacted position to the dotted lines position shown in Fig. 3. This results in withdrawing the spindle 44 from the path of the finger 54, and the spring 59, with the added force of the springs 32, will 75 move the member 55 to the Fig. 2 position. This results in re-engaging the feed rack with the feed dog 18, and withdrawing the locking member 62 to ineffective position. The machine is now again in condition for 80 use.

It will be understood from the foregoing that by reason of the inter-control between a compactible or collapsing part of the machine, the carriage release, and the carriage 85 centering lock, there is no opportunity for the operator to forget to properly condition the machine for portability before inclosing it, and that the necessary setting of one of these parts (the compactible part) necessarily brings about the proper setting of the other parts mentioned, and the proper conditioning of the machine to inclose it, and also to place it in condition for use. 90

By my invention I have provided simple 95 means which have proven effective in use, that compel not only the release of the carriage from restraint of its escapement before the machine can be inclosed in its case, but also compel the proper centering and locking of the carriage by the members 62—66 100 before such a result can be obtained. I therefore insure a proper conditioning of the machine before it can be inclosed in its case for transportation, and prevent injury 105 to the parts of the machine that might result except for such proper conditioning.

Various changes may be made without departing from my invention as set forth in the accompanying claims, and certain features thereof may be employed without others. 110

What I claim as new and desire to secure by Letters Patent is:—

1. In a typewriting machine, the combination of a carriage, and means for locking the carriage in a centralized position in its travel along its support, said means comprising a locking member adapted to be moved from ineffective to effective position 115 at any point in the travel of the carriage, and when in the effective position to automatically coact with its co-operative locking means during a traveling movement thereof in either direction to lock the carriage, and means for maintaining said locking member indefinitely in its effective position. 120

2. The combination with a typewriting or like machine having a carriage and a 125

- compactible part movable independently of the carriage, of means for locking the carriage against movement in both directions in its line of travel, releasable means for preventing a movement of said compactible part to compact position, and a connection between said releasable means and said locking means for rendering said locking means operative and inoperative.
3. In a typewriting or like machine, the combination of a carriage, and means for locking the carriage in a centralized position on its support, said means comprising a spring pressed member normally held by its spring in projected position, and a hand controlled co-operative locking member movable at will into and out of effective position, and when in the effective position adapted by a traveling movement of the carriage in either direction to interlock with said spring pressed member and hold the carriage in a centralized position and against traveling movement in either direction.
4. In a typewriting or like machine, the combination of a carriage, means for locking the carriage in a centralized position on its support including a locking member movable into and out of effective position, and a positively acting locking device movably mounted on the carriage and co-operative with said locking member to hold it in its effective position until said locking device is withdrawn from co-operation therewith.
5. The combination with a typewriting or like machine having a carriage and a compactible part, of means for locking the carriage in position for portability, releasable means for preventing a movement of said compactible part to compact position, and means controlled by said releasable means for rendering said locking means operative when the releasable means are released and for rendering the locking means inoperative when the releasable means are effective.
6. In a typewriting machine, the combination of a carriage; means for locking the carriage in a centralized position in its travel along its support, said means comprising a locking member adapted to be moved from ineffective to effective position at any point in the travel of the carriage and when in the effective position to automatically coact with its co-operative locking means to lock the carriage during a traveling movement thereof in either direction, and means for maintaining said locking member indefinitely in its effective position; carriage feed devices; and means controlled by the movement of said locking member to effective position for automatically freeing the carriage from the restraint of its feed devices.
7. The combination with a typewriting or like machine having a carriage, a platen and a finger piece for turning the platen, and which finger piece is movable into and out of compact relationship, of means for locking the carriage in a centralized position on its support, and means controlled by said finger piece for rendering said locking means ineffective when said finger piece is moved out of its compacted position.
8. The combination with a typewriting or like machine having a carriage and a collapsible part movable independently of the carriage, of means for locking the carriage against traveling movement in both directions from a centralized position on its support, and means whereby said part is prevented from being compacted until said locking means is first rendered operative.
9. In a typewriting or like machine, the combination of a carriage; escapement mechanism therefor; means for locking the carriage in a centralized position on its support, said means comprising a spring pressed member normally held by its spring in projected position, and a hand controlled co-operative locking member movable at will into and out of effective position, and when in the effective position adapted by a traveling movement of the carriage in either direction to interlock with said spring pressed member and hold the carriage in a centralized position and against traveling movement in either direction; and means for automatically freeing the carriage from the restraint of its escapement mechanism when said hand controlled member is moved to effective position.
10. The combination with a typewriting or like machine having a carriage, escapement mechanism, and a collapsible part, of means for locking the carriage against traveling movement in a centralized position on its support and releasing it from its escapement mechanism, and means to prevent said part from being compacted without rendering said locking means operative and without releasing the carriage from restraint of its escapement mechanism.
11. In a typewriting or like machine, the combination of a carriage, escapement mechanism therefor, a hand-actuated carriage release arm carried by the carriage, and means for locking the carriage in a centralized position on its support and including a hand-actuated member carrying a locking finger movable therewith into effective position at any point in the travel of the carriage and engaging its co-operative means during the travel of the carriage in either direction, said member when moving its locking finger to effective position coacting also with said releasing arm to free the carriage from the restraint of its escapement mechanism.

12. In a typewriting or like machine, the combination of a carriage; a collapsible part; means for locking the carriage in a centralized position on its support, said means comprising a spring-pressed member normally held by its spring in projected position, and a hand controlled co-operative locking member movable at will into and out of effective position, and when in the effective position adapted by a traveling movement of the carriage in either direction to interlock with said spring pressed member and hold the carriage in a centralized position and against traveling movement in either direction; means for automatically freeing the carriage from the restraint of its escapement mechanism when said hand controlled member is moved to effective position; and means to prevent said compactible part from being moved to compacted position until said co-operative controlling member is moved to effective position. 70
13. In a typewriting or like machine, the combination of a carriage; means for locking the carriage against movement in both directions from a centralized position on its support, including a locking member movable into and out of effective position; and a shiftable part of the machine which is movable into and out of compact relationship and has a positively acting locking device controlled in its movement by said locking member and co-operative with said shiftable part and co-operative with said locking member to positively hold it in its effective position until said locking device is withdrawn from co-operation therewith. 75
14. In a typewriting or like machine, the combination of a carriage, a platen carried thereby, a finger wheel therefor mounted to be moved from its position of use into a more compact relation, and locking means for locking the carriage against movement on its support, said locking means including a member held in effective position when the finger wheel is in the compact position and permitted to move to ineffective position by a movement of the finger wheel out of said compact position. 80
15. In a collapsible typewriting machine, the combination of a carriage; a compactible part; means for locking the carriage against movement including a locking member movable to effective or ineffective position; means effective to prevent a compacting of said part when said locking member is in the ineffective position and ineffective to prevent a compacting of said part when said locking member is in the effective position; escapement mechanism for the carriage; and means controlled by said locking member for freeing the carriage from the restraint of its escapement mechanism. 85
16. In a typewriting or like machine, the combination of a compactible part; a carriage; escapement mechanism therefor; means for locking the carriage in a centralized position on its support, said means comprising a spring pressed member normally held by its spring in projected position, and a hand controlled co-operative locking member movable at will into and out of effective position, and when in the effective position adapted by a traveling movement of the carriage in either direction to interlock with said spring pressed member and hold the carriage in a centralized position and against traveling movement in either direction; means for automatically freeing the carriage from the restraint of its escapement mechanism when said hand controlled member is moved to effective position; and means to prevent said compactible part from being moved to compacted position until said co-operative controlling member is moved to effective position. 90
17. In a typewriting or like machine, the combination of a carriage; escapement mechanism therefor; a hand actuated carriage release arm carried by the carriage; means for locking the carriage in a centralized position on its support including a hand actuated member carrying a locking finger movable therewith into effective position at any point in the travel of the carriage and engaging its co-operative means during the travel of the carriage in either direction, said member when moving its locking finger to effective position co-acting also with said releasing arm to free the carriage from the restraint of its escapement mechanism; and a shiftable part of the machine movable into and out of compact relationship and having a device which co-acts with said locking finger to prevent a movement of said shiftable part to compact position until said hand actuated member is moved to render the locking means effective and release the carriage. 95
18. In a typewriting or like machine, the combination of a carriage, means for locking the carriage in a centralized position on its support including a locking member movable into and out of effective position; and a shiftable part of the machine movable from its position of use into compact relationship and having a device which co-acts with said locking member to prevent a movement of said shiftable part to compact position until said locking member is moved into effective position, thus compelling the movement of the locking member into effective position before such compaction can take place. 100
19. In a typewriting or like machine, the combination of a carriage, escapement mechanism therefor, a platen carried by the carriage, a finger wheel for the platen mounted to be moved from its position of use into a more compact relation, locking means for locking the carriage against movement on its support, said locking means including a member held in effective position when the finger wheel is in the com- 105
- 110
- 115
- 120
- 125
- 130

5 pact position and permitted to move to ineffective position by a movement of the finger wheel out of said compact position, and means whereby said locking member is effective to render the escapement mechanism effective and ineffective to restrain the carriage.

10 20. In a typewriting machine, the combination of a platen, a finger wheel therefor movable into compact relation, a carriage on which said platen is mounted, a device which in one position forms a lock to keep said finger wheel in its outer position, a locking finger on said device for locking the carriage in a centralized position on its support and held in ineffective position when said locking device is in position to keep the finger wheel in its outer position but projected to effective position when said device is shifted to permit the finger wheel to be moved to compacted position.

15 21. In a typewriting or like machine, the combination of a carriage; means for locking the carriage against movement in both directions from a centralized position on its support including a locking member movable into and out of effective position; and a shiftable part of the machine movable from its position of use into compact relationship and having an element which co-acts with said locking member to positively hold the latter in effective position when said shiftable part is in compact position and frees the locking member and permits it to return to ineffective position when said shiftable part is moved to expanded position of use.

20 22. In a typewriting or like machine, the combination of a carriage, escapement mechanism therefor, a platen carried by the carriage, a finger wheel for the platen mounted to be moved from its position of use into a more compact relation, locking means for locking the carriage against movement on its support, said locking means including a member held in effective position when the finger wheel is in the compact position and permitted to move to ineffective position by a movement of the finger wheel out of said compact position, and carriage releasing means operated by the movement of said locking member to effective position to release the carriage from the restraint of its escapement mechanism and by movement of said locking member to ineffective position to render the escapement mechanism effective to restrain the carriage.

25 23. In a typewriting or like machine, the combination of a carriage, escapement mechanism therefor, means for locking the carriage in a centralized position on its support including a locking member movable into and out of effective position, a positively acting hand controlled locking device co-

operative with said locking member to hold it against movement from its effective position until said locking device is first withdrawn by hand from co-operation therewith, and means controlled by said locking member for rendering the escapement mechanism effective or ineffective to restrain the carriage.

30 24. In a typewriting or like machine, the combination of a carriage, escapement mechanism therefor, carriage releasing means for freeing the carriage from restraint of its escapement mechanism, means for locking the carriage in a centralized position on its support including a locking member movable into and out of effective position, a shiftable part of the machine movable into and out of compact relationship and having a positively acting locking device co-operative with said locking member to positively hold the latter in its effective position until said locking device is withdrawn from co-operation therewith, and means for actuating said carriage releasing means by the movement of said locking member to effective position and thus at this time freeing the carriage from restraint of its escapement mechanism.

35 25. In a typewriting or like machine, the combination of a carriage, escapement mechanism therefor, means for locking the carriage in a centralized position on its support including a locking member movable into and out of effective position, a part of the machine movable from its position of use into compact relationship and including an element that co-acts with said locking member to prevent said compactible part from being moved into compact relationship when said locking member is in the ineffective position, thus compelling the movement of the locking member into effective position before such compaction can take place, and means controlled by said locking member for controlling the release of the carriage from restraint of its escapement mechanism, whereby said escapement mechanism is rendered ineffective to restrain the carriage when said locking member is moved to effective position and is rendered effective to restrain the carriage when the locking member is moved to ineffective position.

40 26. In a typewriting or like machine, the combination of a carriage, and locking means for holding the carriage against movement from a centered position in its line of travel comprising two co-operative locking members one of which is spring supported and an engagement between which members is brought about by a traveling movement of the carriage to said centered position, and settable means co-operative with one of said locking members for maintaining it indefinitely in position to coact with the other of said members and for main-

taining indefinitely one of the locking members out of co-operative relation with the other.

27. In a typewriting or like machine, the combination of a carriage, and locking means for holding the carriage against movement from a centered position in its line of travel comprising two co-operative locking members one of which is spring supported and an engagement between which members is brought about by a traveling movement of the carriage from either right or left to said centered position where the spring supported member will snap into engagement with the other member, and set-table means co-operative with one of said locking members for maintaining it indefinitely in position to coact with the other of said members and for maintaining indefinitely one of the locking members out of co-operative relation with the other.

28. In a typewriting or like machine, the combination of a carriage, and locking means for holding the carriage against movement from a centered position in its line of travel comprising two co-operative locking members one of which is spring supported and an engagement between which members is brought about by a traveling movement of the carriage from either right or left to said centered position, one of said members having a locking projection and the other an opening or recess in which said projection may interlock to prevent a movement of the carriage in both directions when the carriage reaches centered position, and set-table means co-operative with one of said locking members for maintaining it in-

definitely in position to coact with the other of said members and for maintaining indefinitely one of the locking members out of co-operative relation with the other.

29. The combination with the carriage of a typewriting or like machine and its escapement mechanism, of a carriage center lock for holding the carriage indefinitely centered in its line of travel so that the machine may be inclosed within its carrying case and held against endwise movement in both directions thereon, said center lock comprising two members adapted to interlock one with the other, one of said members being spring supported and adapted to be brought into interlocking engagement by a traveling movement of the carriage to its centered position from either the right or left of said position, one of said members being spring supported so as to snap into engagement with its companion member, hand controlled means operable at will for moving one of said members transversely of the line of travel of the carriage and for holding it indefinitely in either the effective or ineffective position, so that the lock may be maintained indefinitely effective or ineffective, and means controlled by said hand controlled means for freeing the carriage from restraint of its escapement mechanism.

Signed at Syracuse, in the county of Onondaga and State of New York, this 25th day of March, A. D. 1922.

JOSEPH B. HOLDEN.
